UNITED STATES PATENT OFFICE.

GUSTAV A. KRUTTSCHNITT, OF NEWARK, NEW JERSEY.

DESIGN FOR A CARD-CASE.

SPECIFICATION forming part of Design No. 30,603, dated April 25, 1899.

Application filed March 24, 1899. Serial No. 710,381. Term of patent 3½ years.

To all whom it may concern:

Be it known that I, GUSTAV A. KRUTTSCHNITT, a citizen of the United States, residing at Newark, in the county of Essex and State of New Jersey, have invented and produced a new and original Design for a Card-Case, of which the following is a specification, reference being had to the accompanying drawings, forming part thereof, and in which—

Figure 1 is a top view of a card-case incorporating my design, the lid of the case being shown in closed position. Fig. 2 is a like view of same, the lid of the case being shown in open position; and Fig. 3 is a longitudinal section of same on the dotted line 33 of Fig. 1.

The leading feature of my design consists of the new and original shape and configuration of the card-case, substantially as shown in the drawings.

The case is in the form of a shallow oblong, presenting smooth exterior surfaces, as shown

in Fig. 3, and at the corners of its front edge being rounded, as at *a a* in Figs. 1 and 2.

The sides *A A* of the case have the concave recesses *b b* adjacent to their front ends, as illustrated in Figs. 2 and 3.

The top and bottom of the case are substantially coextensive, and the hinge *d* for the top *e* is set into the upper inner rear corner of the case, as shown in Fig. 3, so that externally the case adjacent to said hinge will present substantially smooth surfaces and somewhat rounded edges.

What I claim is—

The design for a card-case, substantially as shown and described.

Signed at New York, in the county and State of New York, this 23d day of March, A. D. 1899.

GUSTAV A. KRUTTSCHNITT.
